UNITED STATES PATENT OFFICE.

GEORGE M. GALE, OF SAN ANTONIO, TEXAS.

FOUNTAIN BRUSH.

Application filed February 28, 1922. Serial No. 539,823.

To all whom it may concern:

Be it known that I, GEORGE M. GALE, citizen of the United States, residing at San Antonio, in the county of Bexar and State of Texas, have invented certain new and useful Improvements in Fountain Brushes, of which the following is a specification.

This invention has reference to an improved brush adapted to be used for washing automobiles, store windows, and the like.

The principal object of the invention is to provide a brush which is adapted for either rough cleaning or polishing and embodying brush units of an interchangeable character.

An additional object is to provide a cleaning brush in which a constant flow of water is maintained between the brush units, thereby keeping the brush at all times free from dirt and grit and increasing the quality of the work done as well as a saving of labor.

A further object is to provide a cleaning brush of the character above mentioned including a brush holder and a built up brush portion detachably engaging the holder.

Various other objects and advantages of the invention will become apparent during the continuance of the following description.

In the drawings:—

Figure 1 is a view in perspective of the improved brush.

Figure 2 is a central longitudinal section taken on line 2—2 of Figure 3, and,

Figure 3 is a transverse vertical section taken on line 3—3 of Figure 2.

The brush consists primarily of a holder 10 which may be made of heavy blocked tin or any other suitable material and is preferably shaped as shown in the drawing.

Penetrating the holder at one end is a union 11 constituting a hose connection whereby a liberal supply of water may be conducted to the holder.

The sides of the holder are provided on the inside with longitudinally extending grooves 12 providing ways for slides 13 of the brush proper. The brush proper is of the built up type, consisting of strips 14 of felt extending longitudinally of the holder. At their upper end, the felt strips are spaced apart by separators or feeders 15. The feeders may be of two different

types. Either a solid bar of metal with vertical feed groove 16, or of the frame pattern, being hollowed the entire length.

Passing transversely through the feeder strip and the felt strips, are securing bolts 16', the outer ends of which engage slides 13 for retaining the parts in place. Slides 13 are provided, on the outside, with longitudinally extending tongues 17 which enter the groove in holder 10. The brush proper is thus slidably engaged with the holder and when inserted in the latter is held in place by means of locking bar 18 extending transversely of one end of the holder and hinged thereto as shown at 19. The other end of the locking bar is slotted to receive locking tongue 20, the latter being pivotally connected to the holder and carrying a thumb nut 21.

When the parts are assembled as shown in Figures 1 and 3 of the drawings, the bottom of water space 22 is formed by the upper edge of the brush proper, the felt strips of the brush being held firm by the pointed projections 23 of the feeder strip, which projections penetrate the felt strips and prevent their being pulled out from the holder. The lower or exposed portions of the felt strips are adequately supplied with water from the feed opening of the feeder strips and since there is a constant flow of water it is obvious that the brush will at all times be kept free from dirt and grit injurious to polished surfaces. Consequently the cleaning of an automobile or window can be better accomplished and without the mess or inconvenience attendant upon the use of a sponge or mop.

Two or more brush portions may be provided for each holder, the felt strips of one being of coarse material for rough cleaning and the other of finer material for polishing.

From the foregoing it is believed that the advantages and novel features of the invention will be readily understood and therefore further detailed description is deemed unnecessary.

What is claimed is:—

1. A fountain brush including a hollow head portion having longitudinal side-grooves, tongued slides engageable with the grooves of the holder, felt strips arranged side by side and extending longitudinally between the said slides, means fastening the strips to the slides, said strips providing a

bottom for the hollow head, said head having a hose connection, and the strips being notched to provide conduits between the strips.

5. 2. A fountain brush comprising a hollow brush head constituting a liquid reservoir, a brush portion of separable units slidably inserted in the said head and partially pro-

jecting therefrom, a locking bar hinged to the head for retaining the brush portion in place, means for locking the said bar, and strips separating the upper ends of the said units and grooved transversely to provide liquid conduits.

In testimony whereof I affix my signature. 15

GEORGE M. GALE.
